UNITED STATES PATENT OFFICE

142,059

DESIGN FOR A PORTABLE CLOTHES RACK

Alan C. Botsford, Brooklyn, and Charles J. Chasse,
Whitestone, N. Y., assignors to American Air-
lines, Inc., New York, N. Y., a corporation of
Delaware

Application November 15, 1944, Serial No. 116,347

Term of patent 14 years

(Cl. D80—9)

To all whom it may concern:

Be it known that we, Alan C. Botsford, a citizen of the United States, residing at Brooklyn, in the county of Kings and State of New York, and Charles J. Chasse, a citizen of the United States, residing at Whitestone, in the county of of Queen nad State of New York, have invented a new, original, and ornamental Design for Portable Clothes Rack, of which the following is a specification, reference being had to the accompanying drawings, forming a part thereof. In the drawings:

Figure 1 is a perspective view of a portable clothes rack, showing our new design;

Figure 2 is a top plan view;

Figure 3 is a side view;

Figure 4 is an end view; and

Figure 5 is a bottom plan view.

We claim:

The ornamental design for a portable clothes rack, substantially as shown.

ALAN C. BOTSFORD.
CHARLES J. CHASSE.
